ROAD CONSTRUCTING MACHINE

George F. Bullard, Tampa, Fla.

Application February 12, 1936, Serial No. 63,637

4 Claims. (Cl. 94—44)

This invention relates to road construction and more particularly to an attachment for the scraper blade or mold board of standard road grading machines.

5 In certain sections of this country, excellent roads are produced at low cost by a method commonly called the mix-in-place operation. This method consists in mixing bituminous material, either "cut-back" asphalt or tar, with aggregate 10 or existing road material which is generally sand, working it into the road surface by means of discs, plows and blades until a homogeneous mixture is obtained and finally rolling and sealing the surface to form a smooth roadway. This method 15 is quite satisfactory when the work is done in dry warm weather, but is unsuitable when the weather is cool or during seasons of wet weather.

The object of my invention is to provide means for drying the aggregate and heating the bituminous element of the road mix during the usual 20 blade scraping and road working operations, to thereby produce a very fast and thorough mixing of the bituminous material and the road aggregate together with a more homogeneous resulting mix.

In the following detailed description of my invention, I shall refer to the accompanying drawings, in which—

Figure 1 is a fragmentary side elevation of 30 the supporting framework of a standard road grader showing my blade-heating chamber attached to the scraper blade.

Figure 2 is a transverse view on the line 2—2 of Fig. 1.

35 Figure 3 is sectional view taken on the line 3—3 of Figure 4 showing one of the burners for heating the blade heating chamber.

Figure 4 is a schematic view showing a rear elevation of the blade heating chamber and the 40 manner of supplying the oil under pressure to the burners.

Figure 5 is a schematic perspective view illustrating the manner in which the heated blade 45 operates upon the mixture of bituminous material and road aggregate.

All road engineers are familiar with the construction and operation of standard road grading machines and hence it is unnecessary to include 50 a description herein. I have shown the scraper blade 10 attached to the supporting frame in the usual manner. As is well known, the blade may be adjusted forward or backward in a vertical plane to the desired angle with the road surface 55 and the blade support may be swung forwardly

or rearwardly and elevated or lowered as desired.

The casing or housing of the blade heating chamber 12 may be constructed of cast iron or of sheet steel bolted to the rear side of the blade and braced by straps 14. A plurality of extensions 15 are provided at equal distances along the heating chamber to form inlets for kerosene burners 16. The burners are connected in multiple to a supply pipe 17, leading to a fuel tank 18 located at the rear of the blade frame. 10 An air compressor 20 and reserve air tank 21 maintain a suitable pressure in the fuel tank.

The mold board and blade 10 are protected from the direct blast of the burners by perforated baffle plates 25 positioned in front of each burner. 15 The portion of the rocker arms 26 within the heating chamber may also be protected by asbestos walled chambers 23. Draft vents 24 are provided at equal distances from the burner inlets. In this manner the heat is evenly distributed 20 through the chamber and the blade is uniformly heated throughout its extent.

The temperature of the scraper blade or mold board 10 is maintained between 275° and 350° Fahrenheit. As the road grader travels over the 25 road the blade gathers the mixture of aggregate and bituminous material and causes it to travel toward the trailing end of the blade as indicated in Fig. 5. As the material in front of the blade is constantly pushed upward and continuously 30 tumbles from the top, the particles of the aggregate are brought again and again into contact with the hot blade. This tumbling action is enhanced by the concave shape of the blade. The 35 particles of the aggregate are caused to intermingle by their travel transversely toward the trailing end of the blade. The heat of the blade drives off moisture from the aggregate and causes the particles to become heated. The bitumen constituent is softened so that it flows more readily into intimate contact with the particles of the heated aggregate and becomes thoroughly incorporated throughout the resulting homogeneous mixture. After the rolling operation, a roadway 40 prepared in the manner described not only presents a smooth surface but is exceedingly compact and wear resisting.

It will be evident to engineers that my apparatus does not interfere with the normal operation 50 of the road grading machine and requires no additional power. It greatly enhances the efficiency of the mixing function of the machine by drying the aggregate, improves the homogeneity of the mixture by softening or rendering more fluid the 55

bituminous constituent and bringing it into intimate contact with the heated particles of the aggregate. Finally, my invention enables road-making operation to be successfully conducted when the weather is cool and to some extent, when it is wet.

5 I claim:—

- 10 1. In a machine for road construction, the combination with a concave scraper blade carried by said machine and arranged for adjustment with the surface of the road, a heating chamber secured to the rear side of the blade, means for continuously heating the air in said chamber and causing it to continuously impinge upon the rear side of said blade.
- 15 2. In a machine for road construction, the combination with a scraper blade carried by said machine and arranged for adjustment with the surface of the road and constructed to gather material therefrom and cause a mixing action thereof, a heating chamber secured to the rear side of the blade, a plurality of burners spaced at intervals and connected to said chamber, and means for supplying fuel to said burners, said

burners being positioned and arranged to cause the heated air to impinge upon and circulate over the surface of the rear side of said blade.

3. In a machine for road construction, the combination with a concave scraper blade, of means for heating the blade comprising a heating chamber in juxtaposition with the rear side of the blade, a plurality of burners communicating with said chamber, means for supplying fuel to said burners, and means for equalizing the heat transmitted to the blade comprising a fire-resistant screen positioned in front of each burner.

4. In a machine for road construction, the combination with a concave scraper blade, of means for heating the blade comprising a heating chamber in juxtaposition with the rear side of the blade, a plurality of burners communicating with said chamber, means for supplying fuel to said burners, and means for equalizing the heat transmitted to the blade comprising a chamber having non-combustible walls positioned in front of each burner and vent openings equally spaced from the burners.
